WASHING MACHINE AND PROCESS OF WASHING THEREWITH

Robert J. Anderson, 635 N. West Ave., Sidney, Ohio

Filed Apr. 26, 1955, Ser. No. 503,963

3 Claims. (Cl. 8—159)

This invention relates to a washing machine, and more particularly to the type of machine wherein vibrations are set up in the washing fluid in a clothes container wherein the fluid may be mechanically agitated, although not necessarily limited to mechanical agitation.

For the purposes of illustration, the vibrating mechanism has been shown in association with a washing machine of the type disclosed in my copending application Serial No. 244,934, filed September 4, 1951, for Washing Machine, now Patent No. 2,737,040, issued March 6, 1956.

An object of this invention is to provide a method of and apparatus for vibrating the washing fluid so as to cause rapid vibrations in the washing fluid which may be in addition to the conventional fluid agitating device. For the purpose of illustration, the magnetic vibrating device, or any other suitable device, is mounted in association with the ramp of an agitator which, in this particular instance, also forms the tub or container for the fluid, so as to cause the fluid to be vibrated, setting up pulsations in the fluid, acting upon the fibers of the material to be washed, to thereby aid in dislodging the dirt and foreign matter from the material being washed.

Another object of this invention is to provide a tub and ramp shaker so designed that the clothes and water will be thoroughly shaken or vibrated without the aid of extraneous pumps or water circulating means.

Other objects and advantages reside in the construction of parts, the combination thereof and the mode of operation, as will become more apparent from the following description.

In the drawings:

FIGURE 1 is a vertical cross section taken on the line 1—1 of FIGURE 2.

FIGURE 2 is a horizontal cross section taken substantially on the line 2—2 of FIGURE 1.

FIGURE 3 is a vertical view partly in cross section with portions of the tub broken away.

FIGURE 4 is a horizontal cross section taken on the line 4—4 of FIGURE 3.

FIGURE 5 is a fragmentary cross sectional view taken substantially on the line 5—5 of FIGURE 4.

Referring more in detail to the drawings, a substantially cylindrical tub 10 decreases gradually in diameter as it approaches the bottom. A lip 12 forms a partial closure. The tub is provided with a plurality of inwardly tapered ribs.

The bottom of the tub 10 is provided with a ramp 14 integral with the body of the tub and base and projecting upwardly and outwardly. The ramp and tub are a modification of those shown in my copending application Serial No. 244,934, filed September 4, 1951, for Washing Machine.

As best seen by referring to FIGURES 3 and 4, the ramp 14 consists of a gradually inclined pair of slopes 16 and an oppositely disposed slope 18. The portions 16 and 18 may be practically vertically disposed. The center portion 20 is frustum-conical so as to provide a cavity for the support of the tub. In FIGURE 3, the top plan view of the tub shows a plurality of contour lines 1 to 13 inclusive, that are taken on the elevations 1—13 shown in FIGURE 4. This ramp has been so designed that when the tub rotates in a clockwise direction as shown in

2

FIGURE 4, the steep portion 18 of the ramp causes a violent agitation of the clothes as they fall downwardly.

Means for further agitation of the clothing will later be described.

As best seen by referring to FIGURE 1, the tub is supported upon a shaft 30 having fixedly and non-rotatably mounted thereon a coupling 32 fixedly secured by welding bolts or other means not shown to a conical supporting member 34 projecting upwardly into the frusto-conical portion of the ramp. Member 34 is fixedly secured to the underside of the tub by the outwardly projecting horizontally disposed diaphragm portions 36 by welding or in any suitable manner. The shaft 30 abuts a curved plate 38 secured to the underside of the apex of the frusto-conical portion so that the weight of the tub is transmitted directly to the shaft 30. Bearing 40 is an end face water seal, and the rubber frusto-conical member 42 is in compression only as a means to hold the end face seal in position to prevent leakage around the shaft. The tub is supported on the end of the shaft by reinforcing member or curved plate 38. The frusto-conical water shield 42 is mounted upon an upwardly directed flange, not shown.

The tub is provided with a plurality of inwardly directed tapered ribs 44 positioned in spaced relation from the extremities of each ramp 14. These ribs 44 aid in agitating the water and the clothes as the tub is oscillated, that is, rotated to and fro.

It has been found that movement of the washing fluid with respect to the material to be washed aids in the washing process. Movement, as is well known to the art, is imparted to the washing fluid and to the material to be washed by means of an agitator that may be integral with the tub, like the one disclosed in the present application, or by means of a separate agitator having oscillatory movement or relative movement with respect to the tub.

Another type of movement may be imparted to the fluid, namely, a vibratory movement, where the vibrations may be comparatively small in magnitude, but frequent. These vibrations may be imparted to the fluid either by mounting the vibratory member in the fluid or by vibrating the vessel containing the fluid, or by vibrating the agitator. In the disclosure herein, this has been accomplished by mounting transducers 50 on the under side of the steep or vertical wall portion 18 of the agitator, thereby imparting a horizontal vibratory movement to the steep portion of the ramp, so as to cause the fluid to vibrate. This transducer 50 includes a disc 52 connected to the steep portion 18 by a bellows-like diaphragm 54. An electrical transducer has been shown that may be energized from an external source through a pair of slip rings 46 provided with brushes 48, the slip rings being connected by suitable leads, not shown, to the transducer 50. Such transducers produce a ripple on top of the washing fluid. This ripple is the result of the vibrations of the fluid which are utilized to remove dirt from the material to be washed, such as clothing.

By mounting the transducers on the vertical face of the steep portion 18 at each end of the ramp shaker, the transducers take advantage of the most effective area of cavitation. In the area of cavitation, namely, in the area adjacent the steep portion 18, vortices are formed. When the material to be washed drops over the sloping portion of the ramp, this material is drawn into the immediate vicinity of the transducers or vibrators so as to impart vibrations to the material being washed while in the immediate vicinity of the transducers or vibrators. Here the pressure on the water reaches its maximum point as the ramp agitator starts its reverse movement. By applying energy vibration in this area, it can readily be seen that if 60 cycle alternating current is used in energizing

the transducers, there will be 7200 energy waves per minute directed to the washing fluid attacking the deeply embedded soil of the clothes. In addition to this new energy, the standard washing agitation is also maintained, the clothes moving constantly in and out coming into the area of greatest cavitation and vibratory energy bombardment. By using these energy vibrations, the number of oscillations of the ramp may be reduced without sacrificing upon the performance of the apparatus.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In a washing machine, a tub mounted for to and fro rotary movements, agitating means integral with the body of said tub, said agitating means comprising a ramp having an inclined surface and a substantially vertical surface, and means nested outside of and in contact with the vertical surface of said ramp for imparting a vibrating movement through said ramp to the fluid contents of the tub.

2. A washing machine comprising a tub mounted for to and fro movement, agitating means associated with the body of said tub, said agitating means comprising a ramp having an inclined surface and a substantially vertical surface, and vibrating means for imparting vibrating

10
5
15

movement to the outside of the vertical surface of the ramp to impart vibrations to the contents of said tub.

3. In a washing process, the method of agitating the fluid content and the wash in a washing machine which comprises: imparting oscillatory movement to the fluid content by agitating means rotating to and fro in a horizontal direction, said agitating means having an upwardly inclined portion which in rotating to and fro moves the wash to an elevated position and then precipitately moves the wash downwardly into an area of greatest cavitation, said area of greatest cavitation having been produced by the oscillatory movement of the fluid; and imparting a 60 cycles per second vibratory movement to the fluid content in the area of greatest cavitation, whereby the wash is cyclically moved into the areas of cavitation and subjected to vibrations in said areas.
